UNITED STATES PATENT OFFICE.

ARTHUR M. HARRINGTON AND ROBERT F. SCOTT, OF PHILADELPHIA, PENNSYLVANIA,
ASSIGNORS TO EDWIN HARRINGTON, SON & CO., INC., OF PHILADELPHIA, PENNSYLVANIA, A CORPORATION OF PENNSYLVANIA.

UNIVERSAL JOINT.

1,216,445.

Specification of Letters Patent. Patented Feb. 20, 1917.

Application filed September 16, 1914. Serial No. 861,931.

To all whom it may concern:

Be it known that we, ARTHUR M. HARRINGTON and ROBERT F. SCOTT, citizens of the United States, residing in the city of Philadelphia, county of Philadelphia, and State of Pennsylvania, have invented certain Improvements in Universal Joints, of which the following is a specification.

This invention is an improved universal joint, designed to be used for the production of flexible shafting and other purposes, and a leading object is to provide a simple and efficient construction whose parts are interchangeable, being of uniform construction where performing a common function. A further object is to provide a construction that can be oiled readily and efficiently.

The characteristic features of the improvements are fully disclosed in the following description and the accompanying drawings in illustration thereof.

In the drawings, Figure 1 is a side elevation of a construction embodying the invention, Fig. 2 is a sectional view taken on the line 2—2 of Fig. 1, Fig. 3 is a longitudinal sectional view illustrating a modified construction, Fig. 4 is a sectional view taken on the line 4—4 of Fig. 1, Fig. 5 is a perspective view of a detached bearing stud or journal, and Fig. 6 is a detached bearing of modified construction.

The mechanism, in the form thereof illustrated in the drawings, comprises the similar coupling knuckles 1, having the yoke members or bifurcations 2 disposed transversely to each other and yoked on a substantially cubical block 3 or 3', pintles or small journals 4 or 4' passing through the respective legs of the bifurcations into the block so that each knuckle or coupling member is adapted to move in a plane at right angles to the plane of movement of the other.

As illustrated in Figs. 2, 4 and 5, the pintles 4 have their inner ends turned to form channels 4^a having curved surfaces concentric with the pintles' axes, and similarly beveled faces 4^b adapted to engage so as to leave

an open space or way 5 between their truncated ends, each pintle containing an axial 50 passage 4^c with an angular outlet 4^d to the corresponding bearings 2^a.

As illustrated in Fig. 2, studs 6, having the circular knife edges 6^a, are screwed into the block 3 so as to engage the knife edges 55 in the channels 4^a to hold the pintles 4 in place. These studs 6 are also provided with the passages 6^b in alignment with the passage 5 for the introduction of oil to lubricate the wearing parts, the oil flowing 60 through the passages 4^c and 4^d to the bearings 2^a.

As illustrated in Fig. 3, a single stud 6 may be used in place of the two studs shown in Fig. 2. 65

As illustrated in Fig. 6, studs 4' are provided with the channels 4^c, having substantially conical sides in place of the channels 4^a having substantially spherical sides.

Having described our invention, we claim: 70

1. The combination of transversely disposed yokes, channelled pintles journaled in the furcations of said yokes, the inner ends of said pintles being beveled and provided with notches, and a stud having an edge engaged in said notches and a channel communicating with the channels of said pintles. 75

2. The combination of transversely disposed yokes, a block disposed within said yokes, channelled pintles extending through 80 the bifurcations of said yokes into said block, the inner ends of said pintles being beveled and provided with notches, and a stud in said block having an edge engaged in said notches and a channel communicating 85 with the channels of said pintles.

In testimony whereof we have hereunto set our names this 14th day of September, 1914, in the presence of the subscribing witnesses.

ARTHUR M. HARRINGTON.
ROBT. F. SCOTT.
